UNITED STATES PATENT OFFICE

98,145

DESIGN FOR A SET OF PLAYING CARDS

Rudolf Busch, Mainz, Germany

Application February 19, 1934, Serial No. 50,777
In Germany October 19, 1935

Term of patent 3½ years

To all whom it may concern:

Be it known that I, Rudolf Busch, a citizen of Germany and resident of Mainz, Germany, have invented a new, original, and ornamental Design for a Set of Playing Cards, of which the following is a specification, reference being had to the accompanying drawing, forming part thereof.

The drawing shows plan views of five cards showing my new design, namely an ace, a king, a queen, a jack, and one of the pip cards, these five having been selected as typical of the complete deck of cards.

I claim:

The ornamental design for a set of playing cards, as shown.

RUDOLF BUSCH.
